Primary Examiner — Eric Goodman*Assistant Examiner* — Alyse Joseph(74) *Attorney, Agent, or Firm* — Design IP(57) **CLAIM**

The ornamental design for a portion of a display screen with a graphical user interface, as shown and described.

DESCRIPTION

FIG. 1 is a front view of a first embodiment of a portion of a display screen with a graphical user interface showing my new design;

FIG. 2 is a front view of a second embodiment of a portion of a display screen with a graphical user interface showing my new design; and,

FIG. 3 is a front view of a third embodiment of a portion of a display screen with a graphical user interface showing my new design.

The broken line showing of a portion of a display screen and a mobile device in FIGS. 1 through 3 forms no part of the claimed design. The broken line showing of text and portions of the graphical user interface in FIGS. 1 through 3 represents environmental subject matter and forms no part of the claimed design.

1 Claim, 3 Drawing Sheets(56)
